CIGAR FEEDING DEVICE

Edward F. Cornock, Springfield, Mass., assignor
to Package Machinery Company, Springfield,
Mass., a corporation of Massachusetts

Application December 5, 1931, Serial No. 579,139

3 Claims. (Cl. 131—39)

This invention relates to improvements in article feeding mechanism of the type shown in the Grover application Serial No. 451,688, filed May 12, 1930, and in the Smith application Serial No. 452,682, filed May 18, 1930. In the mechanism shown in these applications a row of cigars was pushed laterally from a magazine upon vertically movable table members which, upon their descent, deposited a row of cigars upon a pair of continuously moving chains, the pusher operating mechanism being so timed that as soon as the last cigar of the deposited row had been advanced clear of the plate by the chains, the plate was again raised and the feeding cycle repeated. With this prior structure it was necessary to make substantial changes and substitutions of parts in order to change the number of cigars in the group fed by the pusher from the magazine.

It is the principal object of the present invention to provide feeding mechanism of the above type which will, without other manual adjustment than the proper positioning of the walls of the hopper, automatically accommodate a substantial range in the number and/or size of cigars fed as a group from the hopper.

In the accompanying drawings which illustrate one embodiment of the invention:

Fig. 1 is a top plan view of the machine;

Fig. 2 is a side elevation on a larger scale of the delivery end of the machine, a portion of the side frame being broken away;

Fig. 3 is a section on line 3—3 of Fig. 2;

Fig. 4 is a section on line 4—4 of Fig. 1;

Fig. 5 is a section on line 5—5 of Fig. 4;

Fig. 6 is a section on line 6—6 of Fig. 4;

Figs. 7 and 8 are detail views showing the corresponding rest positions of the pusher drive and its control finger; and

Figs. 9 and 10 are views similar respectively to Figs. 7 and 8 but showing the members in operative position.

Referring to the drawings, the machine is supported upon a frame 10 to which a magazine supporting bracket 11 (Fig. 4) is secured. A plate 12 carried upon this bracket forms the bottom of a cigar magazine, the ends of which are formed by uprights 13, 14, 15 and 16.

As best shown in Fig. 1, uprights 15 and 16 are carried by a plate 17 adjustably secured to plate 12 as at 18 to permit adjustment of the length of the magazine to vary the number of cigars in the row delivered from the magazine or to accommodate cigars of greater or less thickness. The uprights 13 and 14 are mounted directly on plate 12. Preferably uprights 14 and 16 are adjustably se-

cured as at 20 to their respective supporting plates to permit adjustment of the magazine to accommodate cigars of different length. The front plate 21 of the magazine is held, at an adjustable elevation, to upright 13 by a screw and slot connection 60 22 (Fig. 6) and to upright 15 by a clamping screw 23 (Fig. 4). The rear plate 24 of the magazine is removably secured to upright 14 by screw 25 (Fig. 1) and to upright 16 by a clamping screw 26. As will be obvious, clamping screws 23 and 26 permit 65 movement of the uprights 15 and 16 along the front and rear plates in adjusting the length of the magazine. The rear plate 24 may be removed so that the cigars can be placed within the magazine in orderly rows, and to further facilitate the 70 loading of the magazine a rear bracket 27 (Fig. 4) is secured to bracket 11 and carries on its top a loading table 28 adjustably secured to the bracket 27 as at 29 (Fig. 1).

To force the bottom layer of cigars through the 75 space between plate 12 and the bottom of the front plate 21, a reciprocating plunger is provided. Upon supports 30 extending from the bracket 11 are ways 31 (Fig. 5) in which rack slides 32 run carrying a pusher carriage 33. A pusher plate 34 80 provided with a head 35 is secured to this carriage. To reciprocate the carriage in the ways, the rack slides 32 are provided with teeth 36 (Fig. 4) meshing with pinions 37 (Figs. 1 and 5) fast upon a shaft 38 which is journaled in bearings 39. A 85 pinion 40 (Figs. 4 and 5) upon this shaft meshes with a rack 41 held in position by a guide 42 and pivoted at 43 to the end of a crank member 44 swung at 45 from the frame. The crank is formed with a slideway 46 in which reciprocates a block 90 47 pivotally mounted upon a disk 48 secured to a shaft 49.

As the cigars are fed from the magazine by the plunger they are prevented from over-travel by an abutment 50 formed on the frame and are 95 kept in proper alignment by a guide 51 secured to upright 15. In this position, the cigars are received upon table members 52 carried upon brackets 53 (Fig. 6) pivotally mounted at 54 to similar arms of a pair of identical bell cranks 55 mounted on rock shafts 56. The other arms of these bell cranks are joined by a link 57 so that they move in unison and provide a parallel motion for the table members 52. One of the shafts 56 has fixed to it an arm 58 (Fig. 1) provided at its end with a roll contacting with a crown cam 59 secured to shaft 49. The table members are thus caused to move in timed relation with the plunger which forces the layer or row of cigars from the magazine, and the 110

cam 59 is so designed that the table members will remain in their elevated position during the entire outward movement of the plunger and will then descend to deposit the cigars upon the chain 5 conveyor 60.

Conveyor 60 and cooperating upper chain 61, together with their operating mechanism and associated parts, are fully described in the Smith application Serial No. 452,682 above referred to; 10 and since their specific structure is not part of the present invention a detailed description thereof is not necessary. It will be sufficient to note that the successive rows of cigars are advanced by the continuously moving conveying 15 mechanism to a vertical plunger 62 which moves the cigars successively into the wrapping machine proper, means generally indicated at 63 being provided to interrupt the operation of plunger 62 if the continuity of the file of cigars 20 is broken.

Upon the descent of the table members to deposit the cigars carried thereby upon the chains, the feeding mechanism including the table members must rest inactive until the cigars 25 have all cleared the table members. In order that the inactive period of the feeding mechanism may be automatically timed to permit the feed of cigars from the magazine in groups of various numbers, the shaft 49 is driven through 30 mechanism controlled directly by the group of cigars fed in accordance with the number and size of the cigars in the group. Shaft 49 is provided with a gear 65 mounted for free rotation on the shaft. Gear 65 is continuously 35 driven by a gear 66 mounted on a shaft 67 suitably driven from the associated wrapping machine as by gears 68-69 and sprocket 70 (Fig. 3). A cam 71 and a ratchet 72 are secured to gear 65, and shaft 49 is adapted to be coupled to 40 gear 65 to be driven thereby through engagement of ratchet 72 by a pawl 73 pivoted at 74 to an arm 75 secured to shaft 49. A spring 76 connects the pawl to the hub of arm 75 and urges the pawl into engagement with the ratchet. 45 Pawl 73 is provided with a catch 77 engageable with a latch 78 which is pivoted to the frame at 79 and is adapted to hold pawl 73 out of engagement with the ratchet 72. Latch 78 is connected by a link 80 to one arm of a bell 50 crank 81 (Fig. 2), the other arm of which is connected by a link 82 to an arm 83 adjustably secured to a rock shaft 84 carrying fingers 85 positioned in the path of the cigars fed forward by conveyor 60 from the table members 52. As 55 best shown in Fig. 8, the fingers 85 are rocked clockwise, against the action of a weight 86 (Fig. 2) secured to the bell crank, by contact with the cigars passing forward on the conveyor, to the position shown in full line in Fig. 8 and 60 in dotted line in Fig. 10. In this position, link 80 is elevated as shown in Fig. 7 to depress latch 78 into position for engagement with catch 77 as shown in Fig. 7. Pawl 73 is provided with a roll 87 riding on cam 71 which is so shaped 65 as to periodically rock the catch rearwardly out of engagement with the latch (as shown in Fig. 9), but as long as the latch remains in the dotted line position of that figure the catch is reengaged with the latch as soon as released by the cam. 70 When the last cigar of a group fed from the table members passes from beneath the fingers 85 (as shown in Fig. 10), the fingers swing from the dotted line position of that figure to the position shown in full lines, a stop 88 (Fig. 8) 75 preventing over-travel of the fingers and associ-

ated parts. This movement of fingers 85 through the linkage just described raises latch 78 as soon as the catch is disengaged therefrom by the retraction of the latter by cam 71, and permits pawl 73 to engage ratchet 72. With the pawl in engagement with the ratchet, shaft 49 is locked to gear 65 and is driven thereby causing the feeding mechanism to operate to discharge a group of cigars from the magazine and deposit them on the conveyor. As the so deposited group is advanced by the conveyor, the leading cigar again elevates fingers 85, thus lowering latch 78 into position to engage catch 77 and disengage pawl 73 from ratchet 72, thus disconnecting shaft 49 from gear 65 and arresting the rotation of shaft 49. The feeding cycle if completed in one revolution of the shaft 49, and arm 75 is so positioned on the shaft in relation to block 47 and cam 59 that the feeding cycle is halted at a point when the table members are in their lowered position.

Since the cigars are fed in units, or one at a time, by the reciprocating plunger 62, the cigars accumulate at the forward end of the conveyor, the chains slipping on the cigars as they are 100 halted by the plunger, and the advancing groups of cigars therefore catch up with the depleted accumulation at the forward end of the conveyor thus providing a continuous supply to the plunger.

It is desirable to keep a file of articles extending from the plunger 62 back between the continuous conveyor chains 60 and 61 for a distance which is never allowed to fall below a predetermined minimum, in order that there will always be sufficient pressure on the leading cigar 110 to seat it fully beneath the plunger. The chains 60 and 61 do not extend to the plunger, the file of cigars between the chains and the plunger being forced onward by the chain-gripped cigars behind them. The action of the chains on the cigars being frictional only, it is necessary to have several cigars in simultaneous engagement with the chains in order to force the ungripped file of cigars positively forward. The mechanism 63 previously referred to is adapted to control this condition, and to cooperate with the control finger 85 to preserve a file of at least minimum length back of the plunger 62 even when the number of cigars fed per cycle by the plunger 35 is insufficient to keep up an unbroken file beyond the finger 85.

The control mechanism 63 is constructed as follows. The plunger 62 is mounted for vertical reciprocation in a guide 100 hung from a freely swinging link 101. An arm 102 pivoted to the plunger is fixed upon a shaft 103 to which is also secured an operating arm 104. A roller on the end of this latter arm is held by a suitable spring against a cam 105 on the shaft 67. A third arm 106 secured to the shaft 103 is adapted for contact with a detent 107 fixed on a shaft 108 which is normally held rotated further to the right than the position in which it is shown in Fig. 2 by contact of the cigars with a feeler plate 109. A spring 110 and a stop arm 111 permit the parts to assume the position of Fig. 2 when no cigars are under the feeler plate. In this position the detent 107 underlies the arm 106 and prevents the arm 104 from following the cam. The plunger 62 is by this means held down so that it will not only refrain from feeding cigars but by its lowered position will arrest the feeding of cigars between the guide plates 112 and 113 until the desired number of cigars have formed in line behind it. When cigars again start to move past 145 150

the feeler 109, the latter will be raised and the detent 107 swung to a position out of the way of the arm 106, permitting the plunger 62 to resume its feeding operation.

5 What I claim is:

1. A feeding device for cigars or similar articles which comprises a conveyor for advancing and accumulating a file of articles, means for delivering the articles in units from the conveyor to a wrapping or like mechanism, means operative upon actuation to feed and deposit upon the conveyor a group of articles greater in number than the unit of delivery from the conveyor, means responsive to the absence of articles at one point on the conveyor to actuate the feeding and depositing means, and means responsive to the absence of articles at a subsequent point on the conveyor for arresting the progress of articles along the conveyor to preserve at the delivery end of the conveyor a continuous file of articles of predetermined minimum length.

2. A feeding device for cigars or similar articles which comprises a conveyor for advancing and accumulating a file of articles, means for removing the articles in units from the delivery end of the conveyor, means responsive to the presence of a predetermined length of file of articles for controlling the operation of the removing means, mechanism for depositing articles upon the conveyor in groups of units, and means responsive to the absence of articles at a predetermined point

on the conveyor for controlling the depositing mechanism.

3. A feeding device for cigars or similar articles which comprises a conveyor for advancing and accumulating a file of articles, means for delivering the articles in units from the conveyor to a wrapping or like mechanism, means operative upon actuation to feed and deposit upon the conveyor a group of articles greater in number than the unit of delivery from the conveyor, means for operating said feeding and depositing mechanism including a clutch, a feeler positioned to rest upon the articles on the conveyor at one point along the length thereof, and movable in position upon the occurrence of a gap in the file of articles being advanced, connecting means between said feeler and the clutch whereby said clutch is engaged and actuation of the feeding and depositing means is caused upon the movement of the feeler due to the occurrence of such a gap, a second feeler positioned at a subsequent point along the length of the conveyor and movable in position upon the occurrence of a gap in the file of articles at that point, and mechanism controlled by said second feeler for arresting progress of articles along the conveyor and thus preserving at the delivery end of the conveyor a continuous file of articles of predetermined minimum length.
